UNITED STATES PATENT OFFICE.

ALVIN B. NEIMAN, OF NEW YORK, N. Y.

HEAT-RADIATOR.

1,073,813.

Specification of Letters Patent. Patented Sept. 23, 1913.

Application filed May 24, 1912. Serial No. 699,436.

To all whom it may concern:

Be it known that I, ALVIN B. NEIMAN, a citizen of the United States, residing at the borough of the Bronx, city, county, and State of New York, have invented certain new and useful Improvements in Heat-Radiators, of which the following is a specification.

My improvements relate to the class of radiators for heating, either by means of steam or hot water, in which a continuous coil of thin copper tubing is used in conjunction with transverse radiation plates forced thereon so as to attain intimate contact therewith and thereby facilitate the rapid diffusion of heat. Heretofore these radiation plates have been made in the form of individual disks each with a single hub flange for contacting with a single horizontal member of the copper coil.

A distinguishing feature of my present invention consists in the provision of a series of transverse radiation plates made of thin sheet metal, each plate being common to and contacting with each of the horizontal members of the copper coil, whereby a series of vertical air channels is constituted through which the air is positively conducted from the bottom to the top of the radiator in such manner as to insure the absorbing by the air of a high degree of heat by convection. By this means I am enabled to concentrate the maximum of radiation surface within the minimum of space. That is to say, the radiation plates are so proportioned and arranged as to effectually take up and disseminate the maximum of heat that can be imparted to and by the copper coil, while at the same time all intermediate or lost space in the area of radiation is avoided, each radiation plate being continuous for the whole series of horizontal members of the coil, which latter may thus be arranged nearer together, relatively speaking, so as to reduce the height of the radiator without "crowding" it or reducing its efficiency.

My new construction of radiation plate obviates waste of metal in manufacture as compared with the multiple disk system of radiation plates heretofore used, and hence a radiator of prescribed capacity may be made cheaper, as well as more compact in structure. Furthermore this structure is stronger and more substantial in every way,

the continuous radiation plates binding and uniting the parts, copper coil and all, into an integral rigid unit, which may be handled, transported and manipulated without danger of bending or twisting the coil or deranging the plates—an important practical advantage, especially when the lightness and delicacy of the component parts are taken into consideration.

Another advantage is that the rigid, integral structure thus attained enables me to dispense with the independent coil standards heretofore used, provided with rests or bearings for each horizontal member of the coil, and in lieu thereof to support the radiator as a unit upon the feet secured directly to and between adjoining radiator plates in such manner that variations in floor level may be compensated for, &c. By this dispensing with the heavy castiron standard heretofore used, the gross weight of the radiator, considered as a whole, is still further reduced,—the result being a light, compact, rigid, portable structure of maximum heating capacity, which may be conveniently and safely transported, handled and manipulated, and adapted to the varying conditions and requirements of actual use.

In the accompanying drawings, Figure 1, is a side elevation of a radiator unit, broken away centrally, formed in accordance with my invention; Fig. 2, an elevation of the right hand end thereof; Fig. 3, an elevation of the left hand end thereof; Fig. 4, a sectional elevation on an enlarged scale showing the means of supporting the coil at the ends thereof; Fig. 5, a sectional elevation upon plane of line 5—5 Fig. 4; Fig. 6, a side elevation of the parts shown in Fig. 4; Fig. 7, a detail view of the lower end of one of the end radiation plates.

C, represents a continuous coil of thin copper tubing of uniform diameter throughout, the horizontal members c, being connected by semi-circular coupling members c', which are attached thereto after the radiation plates p, have been forced on said horizontal members c, the attachment of the semi-circular coupling members c', to the horizontal members c, being effected by brazing or otherwise uniting the edges of the piping.

The radiation plates p, are formed of comparatively thin sheet metal, stamped out by means of suitable dies, with flanged open-

ings p' , for the horizontal members c , of the coil,—the flanges p^2 , being forced into intimate contact with the copper tubing when said horizontal members c , are inserted in the openings p' , so as to insure perfect conductivity between the parts.

5 Each radiation plate p , thus contacts with each horizontal member c , of the coil C ,—the series of radiation plates thus binding and 10 uniting the parts into a rigid, integral structure, and positively spacing and reinforcing the coil so that its members cannot be bent or twisted with relation to each other, at the same time preserving the relation and alinement 15 of the radiation plates themselves.

The width of the radiation plates p , and 20 their area between the flanged openings p' , is proportionate to the cross section and heating capacity of the coil, so as to afford ample radiation surface, but no excess there- 25 of,—the adjacent horizontal members c , of the coil being spaced as near to each other as possible consistent with this provision, so as to reduce the height of the radiator to the minimum for a given heating capacity.

It will be seen that the radiation plates p , being in close proximity form between them a series of contracted vertical air spaces, 30 continuous from top to bottom, which practically act as air ducts in which the ascending air is brought, in relatively thin layers, into intimate relation and contact with the opposed surfaces of adjacent plates, and within the area of influence of each longitudinal member c , of the coil, thereby quickly imparting to the air a relatively high degree of heat and insuring a rapid diffusion thereof into the atmosphere above and around the radiator.

40 The coil C , and its radiation plates p , constitute a unit which is essentially self-supporting, and may be so used if desired; but in order to facilitate access of air to the bottom of the radiator, to afford a 45 broader floor bearing, and to compensate for inequalities of floor surface, I prefer to use two or more foot pieces f , f , clamped to and between the lower ends of adjacent radiator plates p , as shown in the last four 50 figures of the drawings. The lower portion of each foot piece is shown as bifurcated to attain a suitable spread or protrusion beyond the width of the radiation plates p , with lightness of structure. The upper portion is also bifurcated to form bearing arms 55 1, 1, between which is a semi-circular seat 2, the radius of which is greater than that of the portion of the coil resting thereon, as shown in Fig. 4. The thickness of the upper portion of the foot piece f , is equal to 60 the space between the opposed faces of adjoining radiation plates, so as to fit snugly between and thereagainst as shown in Figs. 5 and 6. In this position it is secured by 65 a screw bolt b , and nut n ,—the bolt b , pass-

ing through slots p^3 , in the lower ends of the radiation plates p , and through a hole 3, in the foot piece f , said hole 3, being of greater diameter than the diameter of the bolt b , as will be seen by reference to Figs. 70 4 and 5. The slots p^3 , in the lower ends of the radiation plates between which the foot pieces are inserted, are of practically the same width as the diameter of the bolt b , and are open at their lower ends so as to 75 straddle the bolt b , as shown in Fig. 7.

The hole 3, in the foot piece f , of greater diameter than the bolt b , affords a margin for adjustment between the parts. Thus it being understood that the lower horizontal member of the coil rests on the semi-circular seat 2, which is eccentric as related to said horizontal member c , it is obvious that the margin of adjustment afforded by the hole 3, will admit of the placing of the foot piece 80 f , to compensate for any slight variation from the horizontal in the floor support while effecting the true vertical alinement 85 of the radiation plates and coil as a unit upon the foot pieces f ,—one of which is 90 provided at each end of the radiator.

It will thus be seen that the coil is supported upon and by the radiation plates in lieu of the old method of supporting the coil directly upon heavy uprights, or standards; 95 and that the latter are practically dispensed with since the foot pieces f , are mere attachments to the lower extremities of the radiation plates at the ends of the radiator, and are comparatively small and light of 100 weight. Furthermore they afford convenient means for effecting the vertical alinement of the radiator and compensating for inequality of floor support.

What I claim as my invention and desire 105 to secure by Letters Patent is,

1. A radiator of the character designated comprising a coil of tubing of uniform diameter, and a series of sheet metal plates extending continuously from top to bottom 110 of the coil, each formed with a series of hub flanges contacting with the horizontal members of the coil and forming therewith a rigid integral radiator unit, the end plates extending beyond the lowermost horizontal 115 member of the coil and forming a means for supporting the coil.

2. The combination with a radiator having a cylindrical member, of a support therefor having a semi-circular seat to receive said member, said radiator having depending flanges embracing said support and secured thereto.

3. In combination with a radiator having a lower cylindrical member and depending flanges, foot pieces fitting snugly between said flanges, each being formed with a semi-circular seat for said lower cylindrical member, said seat being of greater radius than that of the cross section of said cylindrical 130

member, each foot piece being also formed with a bolt hole of greater diameter than that of the securing bolts, together with said securing bolts, and nuts clamping the adjacent flanges to the said foot pieces, whereby inequalities of floor support may be compensated for and the vertical alinement of

the said radiator unit attained, as and for the purpose set forth.
